UNITED STATES PATENT OFFICE.

GEORGE T. PEARSONS, OF NEW YORK, N. Y.

SPRAYING DEVICE.

Application filed May 22, 1922. Serial No. 582,838.

This invention relates to liquid spraying devices to be utilized as means for spraying trees, shrubbery and the like with an insecticide, and which may also be utilized as a fire extinguisher, and it is the object of the invention to provide a portable device of this character in which liquid carried in a container is adapted to be placed under compression and forcibly ejected therefrom by means within the container normally inactive and which is constructed and arranged to be released when desired.

A further object of the invention is to provide a device of this character in which the means to place the liquid under compression comprises spring actuated piston mechanism including a chamber with which the discharge outlet of the container communicates, said piston mechanism being arranged to be moved to and retained in position with its actuating spring contracted, means being provided to seal the interior of the container from the atmosphere when the piston mechanism is in position with its actuating spring contracted.

Other objects and advantages will herein-after appear.

In the drawings accompanying and forming a part of this specification, Figure 1 is a longitudinal sectional view of a spraying apparatus illustrating an embodiment of my invention, the device being loaded and the means for placing the liquid under compression being shown in its inactive condition.

Figure 2 is a view similar to Figure 1, but showing the parts in position when the means to place the liquid under compression has been released and the liquid discharged from the container.

Figure 3 is a longitudinal sectional view showing a modification of my invention, the device being loaded and the means for placing the liquid under compression being in inactive condition.

Figure 4 is a longitudinal sectional view of the structure shown in Figure 3, but showing the parts in position with the means for placing the liquid under compression released and the liquid discharged from the container.

Similar characters of reference designate like parts throughout the different views of the drawings.

In carrying out the embodiment of the invention shown in Figures 1 and 2, I provide a container comprising a tubular body portion 7 having ends 8 and 9 secured thereto. A plunger or piston 10 arranged with suitable packing is slidably mounted in the container and separates the container in two chambers, the chamber at one side of the piston constituting a liquid carrying chamber, as at 11, while a spring 12 is mounted in the chamber at the opposite side of the piston to drive or actuate the piston to place the liquid in the chamber 11 under compression.

A casing 13 has screw threaded connection 70 at one end with a boss on the piston, as shown at 14, to project into the spring carrying chamber of the container, the opposite end of the casing being closed by a cap 15 to provide a chamber which may be 75 in the nature of a compression chamber in communication with the liquid carrying chamber 11 through ports 16 in the piston and into which casing chamber the liquid is discharged when the liquid in chamber 80 11 is placed under compression by the piston through the influence of the spring 12.

The liquid is discharged to the exterior of the container through a nozzle 17 in communication with the chamber 13 through 85 a tube 18 secured in and constituting a continuation of the nozzle orifice, said tube passing through a perforation in the flanged bushing 19 secured in and extending through an opening in the container end 8 and 90 packing 20 carried by a flanged member 21 attached to the bushing 19, said tube also extending through a stuffing box 22 in the end of the casing 13 into the chamber in said casing.

The spring 12 is confined between the container end 8 and an annular flanged member 23 secured to the casing 13. To place the spring under tension or to contract the same an opening is arranged in the container end 100 9 having a flanged tubular member or sleeve 24 secured therein for the passage of means, such as a rod, to engage the piston mechanism. The sleeve 24 also serves as the filler opening for the liquid carrying chamber 11 and is closed by a cap 25 having threaded connection with a portion of the sleeve extending beyond the end 9. To secure the piston in position with the spring contracted an abutment 26 is arranged on the discharge 110

tube 18 to extend diametrically opposite from the tube, which abutment is adapted to pass through opposite slots 26' in the wall of an opening in the end of a casing 27 mounted axially in the piston or plunger and which abutment is adapted to engage within said casing at opposite sides of the opening therein, as shown in Figure 1.

To prevent leakage and evaporation of the liquid through the outlet tube 18 a spring influenced closure 28 is arranged in the casing 27 to engage the end of the tube, the tube being releasably retained in position with the closure in engagement therewith by lugs 28^a extending oppositely from the nozzle, which are adapted to pass through notches in a flanged member 29 of angular shape in cross section arranged at the outer side of the end 8 of the container and to engage below the flange of said member by giving the nozzle a slight rotary movement, which movement of the nozzle is facilitated by portions 30 projecting laterally therefrom to form a hand-grip. This rotary movement of the nozzle also serves to cause the tube abutment 26 to engage at the inner side of the wall of the opening in the casing 27.

In this position of the parts the chamber 11 may be supplied with the liquid to be ejected from the container through the sleeve opening 24, such liquid also passing through the piston port 16 into the chamber of casing 13. After the liquid carrying and piston chambers 11 and 13 have been filled with liquid the closure cap 25 is secured in place when the device is in condition for operation. To use the device the nozzle is given a partial rotation to free the nozzle lugs 28^a from the locking flange 29, this movement positioning the abutment 26 on the discharge tube 18 to permit the same to pass through the opening in the casing 27 by a longitudinal movement of the nozzle freeing the end of the tube from the closure 28. The outward movement of the nozzle is limited by a stop member 31 on the tube engaging the flanged member 21. The opening in the bushing 19 through which the tube passes is of greater diameter than the tube leaving a space between the tube and the wall of the inlet opening, this space being sealed in the normal inoperative position of the parts shown in Figure 1 by a disk of sealing material 32, such as cork, seated in the bottom of a recess in the nozzle, and by an annular sealing member 33, which may also be cork, engaging about the wall of said nozzle recess and retained therein by serrating the surface of the side wall of said recess, said annular sealing member being adapted to engage about the bushing 19. The space between the discharge tube and wall of the bushing opening is connected to the spring carrying chamber of the container through per-

ber 21, said disk having the peripheral wall arranged of concave shape to provide a space between the periphery of said disk and the side wall of the flange of the member 21 with which ports 35 in the flange of the member 21 communicate, whereby the spring carrying chamber of the container is open to the atmosphere during the discharge of the liquid from the container to permit of entrance of air into such chamber to displace the liquid discharged from the container and prevent the creating of a vacuum which may have a tendency to retard the movement of the piston. By the provision of the casing chamber 13 there will be a supply of liquid at the entrance end of the discharge tube 18 whereby the discharge of the liquid may be effected in whatever position the container may be held.

A drain plug 80 is provided for removing any liquid which may leak by the piston. This plug also serves to permit air to enter the spring chamber and for this purpose a perforate cap 81 is threaded on the outer end of the plug. The perforation in the cap is closed by valve 82 positioned in the tubular portion of the plug and normally urged by a spring 83 to engage a seat arranged about the inner end of the cap perforation.

The structure shown in Figures 3 and 4 is the same as that shown in Figures 1 and 2 with the exception that the piston mechanism has a tubular member 37 secured at one end to the side of the piston opposite to the casing 13^a and slidably engages in the stuffing box 38 secured in an opening in one end of the container, which tubular member is projected from the container as the piston mechanism is actuated by the spring to discharge the liquid from the container. This member 37 also serves as a means to move the piston to position to contract the piston actuating spring 12^a, and the piston is retained in such position by locking lugs 38' extending laterally from an annular flanged member 39 secured to the outer end of the member 37 passing through notches in a flanged member 41 arranged on the end of the container and caused to engage below the flange of said member. The flanged member 39 has a portion 40 to engage in the tubular member 37 to position the same relative to such tubular member. By the arrangement of the flanged member 39 as described there is provided an annular recess 42 the member 39 being in the nature of a cap to engage the outer end of the stuffing box with a disk 43 seated in the recess portion of cap to seal the stuffing box. To seal the outlet tube during the inactive condition of the device to prevent leakage and evaporation of the liquid in the container through said outlet tube a spring influenced valve 45 is carried in a recess of a plug 46 fixed in the tubular member 37 and with which valve the

end of the outlet tube engages when the piston is in spring contracting position, a perforation 47 being arranged in the piston to permit of the passage of the outlet tube, as shown in Figure 3.

To permit of the entrance of air into the container to replace the discharged liquid an air inlet port 44 is arranged in the wall of the tubular member 37 which is open to the atmosphere during the discharge of the liquid and in communication with the space in the tubular member 37 above the plug 46 and in communication with the container through a tube 48 passing through the valve 10 plug and communicating with a port 49 through the piston. When the piston mechanism is in spring contracting position the air inlet port 44 is sealed by the stuffing box 38, as shown in Figure 3. The tubular member 37 may also have a port 50 for the flow of the liquid in the chamber of the casting 13^a through the piston port 47.

To set the device in operation all that is necessary is to give the tubular member 37 a 25 partial rotation which is facilitated by the arranging of a hand-grip 51 at the outer side of the locking member to cause the locking lugs 38' to register with the notches in the flanged member 41. The container is arranged with a filler opening 52 which is 30 closed by a removable cap 53.

From the foregoing description it will be obvious that in the normal condition of the device the liquid is not under compression, the piston mechanism being releasably locked in position with the spring contracted and though the spring is exerting a force upon the piston mechanism this is not applied to the liquid. However, as soon as the piston 40 mechanism is released the tension of the spring upon the piston mechanism causes the piston to place the liquid under compression and thereby to forcibly discharge the liquid from the container.

To draw any liquid from the spring carrying chamber of the container which may seep past the piston a drain plug 80^a is provided. This plug is also arranged to permit of entrance of air into the spring carrying chamber for which purpose a perforate cap 81^a is threaded on to the outer end of the plug, the perforation in said cap being closed by a valve 82^a contained within the tubular portion of the plug and normally urged to position to engage a seat arranged about the inner end of the cap perforation by a spring 83^a. Should a vacuum for any reason be created in the spring chamber of the container this vacuum will unseat the valve 82^a and permit the entrance of air in said chamber. To drain liquid from said chamber the cap is removed.

Having thus described my invention, I claim:

1. The combination of a liquid carrying 65 container, means to place the liquid in the container under compression including a compression chamber into which the liquid is discharged from the container, outlet means in communication with said chamber 70 of the compression means, and means operative to seal the outlet means and means to retain the compression means in inactive position, said latter means being operative to release the compression means to eject the 75 liquid from the said container.

2. The combination of a liquid carrying container, spring actuated piston mechanism therein including a chamber movable with the piston to place the liquid under compression, outlet means in communication with the chamber of the piston mechanism, and means operative to retain the piston mechanism in position with its actuating spring contracted, and means to seal the container 80 outlet with the piston in such position, said retaining means being operative to release the piston mechanism and open the outlet means to the atmosphere.

3. The combination of a liquid carrying 90 container, spring actuated piston mechanism therein including a chamber movable with the piston and in communication with the liquid in the container, an outlet for the container including a tube constituting a continuation thereof and in communication with the piston chamber, and means to retain the piston in position with its actuating spring contracted to maintain in pre-deter- 95 mined position a closure to seal the outlet tube when the piston is in such position, said means being operable to release the piston and the discharge tube from its closure for the purpose specified.

4. The combination of a liquid carrying 105 container, a piston to separate said container into two chambers one chamber adapted to carry liquid at one side of the piston, a spring to drive the piston in the chamber at the opposite side of the piston, a discharge 110 tube for the liquid in the container having an outlet from the end of the container and the side of the piston at which the spring is located and in communication with the liquid in the container at the opposite side of the piston through the piston, means to releasably hold the piston in position with the spring contracted, and a closure to seal the outlet tube when the piston is in said 115 position.

5. The combination of a liquid carrying 120 container, spring actuated piston mechanism therein to place the liquid under compression including a chamber movable with the piston mechanism, a discharge tube in communication with said chamber, means to releasably retain the piston in position with the spring contracted, and means carried by

the piston mechanism to seal the outlet tube when the piston is in its spring contracting position.

6. A liquid carrying container, piston mechanism in said container to place the liquid therein under compression including a casing having a chamber in communication with the container and movable with the piston mechanism, discharge outlet means from said container including a tubular member in communication with the chamber of the piston mechanism in all positions thereof, means operable to releasably hold the piston mechanism from movement and means to shut off communication between the container and the exterior thereof.

7. The combination of a liquid carrying container spring actuated piston mechanism in said container to place the liquid therein under compression, a chamber movable with the piston in communication with the liquid carrying container, outlet means for said container comprising a tubular member in communication with the chamber and the exterior of the container, to conduct the liquid from the container to the exterior of the container when the liquid is under compression, and means operable to shut off communication between the liquid carrying container and the exterior thereof.

8. The combination of a liquid carrying container, spring actuated piston mechanism therein to place the liquid under compression including a chamber movable with the piston mechanism, outlet means for said container comprising tubular means to connect the chamber with the exterior of the container, means to releasably retain the piston mechanism with its spring contracted, said means being operable to release the piston mechanism to eject the liquid from said container and means carried by the piston to shut off and open up communication between the liquid carrying container and the exterior thereof.

9. The combination of a liquid carrying container, spring actuated piston mechanism including a chamber to place the liquid in the container under compression, a discharge tube communicating with the chamber of the piston mechanism in all positions of the latter, means slidably engaging in an opening in the container to move the piston to position to contract the spring and releasably secure the piston mechanism in such position, and a closure operable to seal the outlet tube when the piston mechanism is in such position.

10. In a liquid carrying container, a piston mechanism to place the liquid therein under compression, a casing rigidly attached to said piston mechanism in communication with the liquid carrying container, outlet means for said container comprising a tubular member in communication with the atmosphere and with said casing to conduct the liquid from said casing to the exterior of the container, means to releasably maintain the piston mechanism in a pre-determined position and valve means carried by the piston mechanism to open up and shut off communication between the liquid carrying container and the exterior thereof.

11. In a liquid carrying container, a piston mechanism to place the liquid therein under compression, a casing having a chamber attached to and movable with the piston mechanism, said chamber having communication with the liquid carrying container, outlet means for said container comprising a tubular member connecting said chamber with the exterior of the container to conduct the liquid from said container to the exterior thereof, means to releasably hold the piston mechanism in a pre-determined position and means to shut off and open up communication between the liquid carrying container and the exterior thereof.

12. The combination of a liquid carrying container having outlet means, piston mechanism therein to divide the container into two chambers one of said chambers being adapted to carry liquid at one side of the piston, a spring in the other chamber at the other side of the piston to actuate the piston to place the liquid in the container under compression, a discharge tube in communication with the outlet means of the container, means movable with the piston mechanism to establish communication between the said tubular member and the liquid carrying container to conduct the liquid to the exterior of the liquid carrying container, means to releasably hold the piston with the spring contracted and means to shut off and open up communication between the liquid carrying container and the exterior thereof.

Signed at New York city, in the county of New York and State of New York, this 8th day of May, 1922.

GEORGE T. PEARSONS.
